UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

PANEL-BOARD.

1,321,488.

Specification of Letters Patent. Patented Nov. 11, 1919.

Original application filed June 13, 1911, Serial No. 632,883. Divided and this application filed June 6, 1917. Serial No. 173,148.

To all whom it may concern:

Be it known that I, HENRY F. STARRETT, a citizen of the United States, residing at Chicago, in the county of Cook and State 5 of Illinois, have invented new and useful Improvements in Panel-Boards, of which the following is a full, clear, concise, and exact description, reference being had to the accompanying drawing, forming a part of 10 this specification.

My invention relates to improvements in panel-boards and has for its object to provide an improved form of panel-board which may be manufactured at much less 15 cost than the panel-boards which are at present manufactured, which will have the current bus-bars and branch conducting bars concealed, and which will improve the appearance and manufacture of panel-boards 20 in general.

Various advantages and improvements will appear from the following specification and claims.

For the purpose of disclosing my invention I have illustrated one embodiment thereof in the accompanying drawings. In said drawings—

Figure 1 is a front elevation of a panel-board embodying my improvements;

Fig. 2 is a rear elevation of the panel-board with the back insulation left off;

Fig. 3 is a transverse sectional view taken on the line 3—3 of Fig. 1;

Fig. 4 is a longitudinal sectional view 35 taken on the line 4—4 of Fig. 2;

Fig. 5 is a detail sectional view taken on the line 5—5 of Fig. 1;

Fig. 6 is a detailed sectional view taken on the line 6—6 of Fig. 1; and

Fig. 7 is an enlarged detail view showing the manner of connecting the anchor-studs to the distributing conductors.

In the embodiment of the invention illustrated I provide a base or cover-plate 1 on 45 which the various parts of the panel-board are mounted. This base or cover-plate is composed of suitable insulating material, preferably slate, and in cross-section is of much less thickness than the slate bases 50 heretofore used in the commercial art. I am able to reduce the thickness of the slate base by the various improvements I have made in panel-boards.

The bus-bars and branch conducting bars

or distributing connectors of the panel-board are mounted on the rear face of the base. In the structure illustrated I have shown a panel-board having bus-bars for a three-wire connection, with six sets of two-wire branch conducting bars, these conducting bars being arranged as is usual in the double-branch type of panel-board.

Referring particularly to Fig. 2, which illustrates more clearly the bus-bars and branch conducting bars or distributing connectors, the three bus-bars 2, 3 and 4 are illustrated as extending the entire length of the board. These bus-bars, instead of being formed, as heretofore, of heavy copper bars, are formed of thin copper ribbons and 60 may be laminated if desired. One of the advantages of using the copper ribbons is that the bus-bars may be formed of laminated ribbons and may be proportionately increased in thickness with the current-carrying capacity; that is, at the lower end, where the current carrying capacity must be great, a number of laminations may be used, which number may be decreased as the bus-bar extends to the top. The lower ends of 70 the bus-bars are adapted to be connected to a respective line-connection, and for this connection I prefer to use a structure illustrated in the accompanying drawings.

Referring particularly to Figs. 4 and 7, it 75 will be noted that I provide an anchor-stud 5 which is headed as at 6 and has a portion 7 extending through a hole in the base 1. The lower end of this stud is restricted and screw-threaded as at 8 and is adapted to receive a nut 9 for assisting in holding the anchor-stud in position on the base. Preferably interposed between the nut 9 and the base 1 is a washer 10. The thin ribbon forming the bus-bar has a hole in it at the proper position to fit over the threaded stem 8, and after the ribbon is placed in position it is secured by a casting process; that is, a mold 90 is secured in position over the bottom of the stud 8 and a securing metal, which may be of brass or any other desired soldering metal, is poured into the mold, thereby joining the bus-bar and stud by a solid mass and forming an integral metal conductor. The front 95 of the anchor-stud 5 has a screw-threaded opening, as at 11, to receive a screw 12. The screw 12 serves to hold the terminal connector 13 in place. I have described in detail 100 105

the anchor-stud 5, as this form of stud is not only used for removably securing the wire connecting-terminal in position, but is also used for securing in position circuit-controlling apparatus used on a panel-board, such, for instance, as the fuse-receptacles.

The branch wire connections extend from each side of the bus-bars in pairs, there being illustrated in the accompanying drawing six pairs, three on each side of the bus-bars. One of a pair of connections is taken from one of the outside bus-bars, and the other of the pair is taken from the inside bus-bar. The two wire branches are each provided with fuse-terminals arranged for Edison plug fuses, and, as all of the sets of branches are alike, it will only be necessary to describe in detail one set thereof.

An anchor-stud 14 similar in construction to the anchor-stud 5 is connected to the bus-bar 4. A second anchor-stud 15 is arranged to one side of the bus-bar and is connected to a branch conducting bar 16, which conducting bar or distributing connector extends to the inner end of a binding-screw 17. This screw is connected to the branch conducting bar 16 in a manner similar to that described for connecting the anchor-stud 5 to the bus-bar, that is, the branch conducting bar is secured to the head of the screw 17 by the casting process hereinbefore referred to. The headed screw 17 extends through from the rear of the base 1, a suitable nut 18 being screwed thereon to hold it in position, said screw also being provided with a thumb-nut 19 for screwing the connecting branch wire thereto.

The second connection of the branch extends from the central bus-bar 3. A cross strip or branch conducting bar 20 is connected at one point to the central bus-bar 3 and extends to an anchor-stud 21. A second anchor-stud 22 is mounted on the base and is connected by a branch conducting bar 23 with the second binding-post 24. It will be noted that, due to the alinement of the bus-bar 4, it passes over the anchor-stud 21 which is connected to the branch conducting bar 20. As these two portions are of opposite polarity, I interpose between the stud 21 and its branch conducting bar and the bus-bar 4 an insulating strip 25, which is preferably formed of mica riveted or otherwise secured to the bus-bar. This may be very thin and effectually insulates the two conductors of opposite polarity. This strip, as will be noticed, is of sufficient length to extend to the next cross-over, if desired. It will be noted that the branch conducting bar 20 may be of sufficient length to extend to the stud having branch wire connection opposite the pair which have been described.

The studs 14 and 15 and 21 and 22 are electrically connected through suitable fuses 65 on the face of the board; I have provided in

the embodiment illustrated a fuse-receptacle or terminal for that type of fuses known as the Edison plug fuse. This receptacle is mounted on the front of the board so that the fuse can be conveniently inserted or removed and is of special design, permitting it to be readily removed from the board if so desired.

Referring particularly to Fig. 3, the fuse-receptacle consists of a cylindrical shell, 75 preferably of porcelain, provided with a front recess or opening 26, in which is adapted to be arranged a threaded shell 27 and a center contact 28. A cross-web 29 forms a bottom for the receptacle 26 and provides 80 a means for holding the retaining-screws in position. The threaded shell 27 is held in position and electrically connected to the stud 15 by means of a screw 30. This screw extends through an opening in the shell 27 85 having tapered walls which are drawn into a cone-shaped opening in the web 29 and screws into the anchor-stud 15. The center contact 28 comprises the head of a screw 31 which is insulated from the bottom of the 90 shell 27 by the interposition of a mica or other insulating washer 32, and extends through the web 29 into a contact plate or nut 33. This contact plate or nut is provided with an integral sleeve 34 which extends through the web 29 and is spun over as shown. A screw 35 is adapted to pass through the sleeve and extend into the anchor-stud 14. It will thus be seen that one terminal of the plug receptacle is connected 100 to one of the anchor-studs, and the other terminal of the plug receptacle is connected to the other anchor-stud so that when the fuse-plug is inserted in position a connection will be formed from the bus-bar 4 to the 105 connection-terminal 17.

In building the board the necessary studs for connection of the various devices are properly connected to the bus-bars, conducting bars, or distributing connectors and 110 branch wire connections. After these parts have all been assembled the cover-plate is mounted on a shallow sheet-steel casing 36. This casing is provided with side flanges 37, which engage the back of the panel-board 115 and the casing is held in position by suitable anchor-bolts 38. These bolts extend through the face of the base as illustrated in Fig. 5 and have a nut 40 screwed on their rear ends to secure the casing in place. At 120 the point where the anchor-bolts extend through the casing, the casing is dished as at 39 so that after the nut 40 is screwed in position this nut will be flush with or below the surface of the casing. The ends of the 125 bolts 38 which extend through the nuts 40 are swaged or riveted, as shown at 46, to rigidly hold said bolts in position. Suitable spacing-collars 41 and washers 42 are interposed between the casing and the base to 130

prevent the nut 40 from buckling the casing when it is screwed tight. After the casing is secured in position I may pour in, if desired, a suitable insulating compound 47 which completely fills the casing and in which the distributing conductors on the back of the board are embedded.

For securing the panel-board in position on the wall, or to any other place where it may be attached, I provide suitable screw-holes 43 in the base, which holes extend through the casing 36. A tube 44 extends through the base and casing 36 and is spun over the front of the base and the casing, as at 45, the point in the base and casing where the spacing-tube is spun over being preferably dished, as at 46. This serves to aid in supporting the casing on the base as well as forming a screw-hole. A suitable spacing-collar 48 and washer 49 surround the tube and are interposed between the casing and the tube.

I have shown one particular arrangement of bus-bar and branch conducting bars. It will be understood, however, that various circuit arrangements of the distributing conductors may be used; also, it will be understood that, where desired, instead of using the fuse-receptacles of the particular type illustrated, I can use any other form of circuit-controlling apparatus; or, where it is not desired to use fuses, the fuses may be dispensed with entirely. In each instance, however, the bus-bars and branch conducting bars will be arranged on the rear of the board, and the only surface contacts or conductors on the face of the board, with the exception of switches and fuse-receptacles, are the anchor-studs.

This application is a division and continuation of my application Serial No. 632,883, filed June 13, 1911, title Panel-boards.

I claim as new and desire to secure by Letters Patent of the United States:

1. A panel-board base unit comprising, in combination, a shallow metal casing, an insulating cover-plate therefor, strips of conducting material comprising bus-bars and conducting bars supported on the rear face of said cover-plate and within the casing, and anchor-studs permanently and rigidly secured to said bars extending through said cover-plate and securing said bars in place, said anchor-studs having threaded portions by which the electrical equipment of the board is removably secured thereto, said anchor-studs securing the bars in position independently of the electrical equipment to permit the mounting and removal thereof on the base unit without displacing the bars.

2. A panel-board base unit comprising, in combination, a shallow metal casing, an insulating cover-plate for said casing, conductor strips comprising bus-bars and conducting bars supported on the rear face of said

cover, anchor-studs extending through said cover and soldered to said bars at their rear ends to permanently and rigidly secure said bars in position, said anchor-studs at their front ends having means for removably securing the electrical equipment of the board thereto and said studs securing the bars in position independently of the electrical equipment to permit the mounting and removal of the electrical equipment without displacing the bars.

3. A panel-board base unit comprising, in combination, a shallow metal casing, an insulating cover-plate therefor, strips of conducting material comprising bus-bars and conducting bars supported on the rear face of said cover-plate, an insulating casing, a threaded shell arranged in said casing, attaching means extending through the board and connected to the bars, means removably supporting the casing in position and electrically connecting the threaded shell with the conducting bars, said bus-bars and conducting bars being secured in position independently of said insulating casing to permit the mounting and removal thereof without displacement of the bars.

4. A panel-board comprising a flat insulating base having all of the bus-bars and branch conducting bars arranged on the back thereof, anchor-studs extending through said base and having threaded sockets in their faces, an insulating casing, a threaded shell and center contact arranged in said casing, and screws for removably supporting said casing in position on the base and electrically connecting the threaded shell and contact with the bus-bar and branch conducting bar arranged to enter said threaded sockets in the anchor-studs.

5. In a device of the character described, the combination with a cylindrical porcelain casing open at each end and having a center web intermediate of its ends, a threaded shell contact in one end of said casing, the bottom of said shell having an opening therein, the walls of said opening being cone-shaped, said web having a cone-shaped seat therein to receive the walls of said opening, a screw passing through said web and having its head engaging the cone-shaped walls of the opening in the bottom of the shell and adapted to mechanically support said casing in position and electrically connect said shell with the circuit conductor, a center contact, and a second screw for connecting said center contact with the circuit conductor and mechanically supporting said casing in position.

6. In a device of the character described, the combination with a cylindrical porcelain casing open at each end and having a web formed therein intermediate of its ends, a threaded shell contact arranged in one end of said casing, a screw passing through the

bottom of said threaded contact and through said web for electrically connecting said contact with the circuit conductor and mechanically supporting said casing in position, a center contact, a conductor-plate arranged on the back of said web and electrically connected with said center contact, a sleeve formed on said plate arranged to pass through an opening in said web and having a portion thereof headed over said opening to hold said plate in position, and a screw passing through said sleeve and adapted to mechanically support said casing in position and electrically connect said center contact with the electrical circuit.

7. A panel-board comprising a flat insulating base having all of the bus-bars and branch conducting bars supported on the back thereof, a sheet-steel reinforcing casing secured on the back of said base, anchoring studs passing through said base electrically connected with the bus-bars and branch conducting bars and having threaded sockets in their faces, a cylindrical porcelain casing, a threaded shell contact and a center contact mounted within said casing, and screws adapted to enter the threaded sockets of the anchor studs for electrically connecting the threaded shell and center contact with a conducting bar and a bus-bar, respectively, and for removably mechanically securing the casing in position on said base.

8. A panel-board comprising a flat insulating base having all of the bus-bars and branch conducting bars mounted on the back thereof, a reinforcing steel casing secured on the back of said base and inclosing said conducting bars, anchor-studs extending through said base and permanently mechanically and electrically connected with the bus-bars and branch conducting bars and having threaded sockets in their faces, a threaded shell contact and a center contact mounted on the face of said base, and means for mechanically and electrically connecting said threaded shell and center contacts each with one of a pair of anchor-studs.

9. A panel-board comprising a flat insulating base having all of the bus-bars and branch conducting bars mounted on the back of said base, current-conducting members permanently electrically and mechanically connected with the bus-bars and branch conducting bars and extending through said base to the face thereof, a porcelain casing recessed on its under side and arranged to fit over and inclose two of said current-conducting members, a threaded shell and center contact arranged within said casing, and means inclosed within said porcelain casing for electrically connecting said contacts with the connectors and removably mechanically supporting the casing in position upon said base.

65 10. A panel-board comprising a flat in-

sulating base, a plurality of bus-bars and branch conducting bars all mounted on the rear of said base, said conducting bars and branch bus-bars comprising all of the bars of the panel-board, securing-members for holding said bus-bars and branch conducting bars in place extending through the base and permanently connected with the bus-bars and branch conducting bars, an insulating casing recessed on its bottom to cover at least two of said securing members and having a recess in its top for receiving a threaded shell and center contact, and means for detachably electrically connecting said shell and center contact each with one of a pair of branch bus-bars and for detachably mechanically supporting said insulating casing on the front face of said base.

11. A panel-board comprising a flat insulating base, a plurality of bus-bars and branch conducting bars all mounted upon the back of said base, said bus-bars and branch conducting bars comprising all of the bus-bars and branch conducting bars of the panel-board, studs extending through said base permanently connected with the bus-bars and branch conducting bars and provided with threaded sockets, an insulating casing having its under side recessed to fit over at least two of said studs, a threaded shell and center contact mounted in the front of said casing, and screws for electrically connecting said shell and contact with said studs and removably mechanically securing said casing in position on the front of said base adapted to enter the threaded sockets of said studs.

12. A panel-board comprising a flat insulating base, a plurality of bus-bars and branch conducting bars mounted on the back of said base, said bus-bars and branch conducting bars comprising all of the bars of the panel-board, current-conducting studs permanently connected with said bus-bars and branch conducting bars extending through said base headed over the base and having threaded sockets in the front thereof, an insulating casing recessed on its under side to accommodate the heads of at least two of said studs and make a flush contact with the surface of said base, said casing having a recess in the front thereof, a threaded shell and center contact arranged in said recess, and screws for electrically connecting said contact and shell with the studs and removably mechanically securing said casing in position upon the base adapted to enter the sockets of said studs.

13. An electrical device comprising an insulating base having an opening therethrough; a conducting plate supported by said base, means for securing said plate to said base comprising a tubular metal member extending through said opening, a second insulating base, and a means extending

125

130

through said tubular member for securing said first base to said second base.

14. In a device of the class described an insulating support, an apertured member of 5 conducting material supported thereby, a second insulating base having an opening therein, a second member of conducting material supported thereby, means for securing said second member to said second 10 base comprising a tubular metal device secured to said second member and extending through said opening, and means for securing said second base to said first base comprising a securing member extending 15 through said tubular device and aperture.

15. In a device of the class described, an insulating support, an internally screw-threaded member of conducting material supported thereby, a second insulating base 20 having an opening therein, a second member of conducting material supported thereby, means for securing said second member to said second base comprising a tubular metal device secured to said second member 25 and extending through said opening, and means for securing said second base to said first base comprising a screw extending through said tubular device and threaded into said internally-threaded member.

30 16. In a device of the class described, an insulating support, an internally-threaded member of conducting material supported thereby, a second insulating base having an opening therein, a second member of conducting material supported thereby, means for securing said second member to said second base comprising a tubular metal device secured to said second member and extending through said opening, and means for securing said second base to said first 35 base comprising a screw extending through said tubular device and threaded into said internally-threaded member, said second base having a recess therein and a contact 40 in said recess electrically connected with said second member for engaging an insertible device.

45 17. In a panel-board, a base, a bus-bar system concealed from the front of the base, 50 studs electrically connected to the bus-bars and extending through the base to the front thereof and secured thereto, circuit-controlling equipment, and means whereby said circuit-controlling equipment may be secured to and removed from the said studs from the front of the base, the position and inter-relationship of said bus-bar system 55 and base being unaffected thereby.

60 18. In a panel-board, a base, a bus-bar system located at the rear thereof, conducting studs electrically and mechanically connected to the bus-bars secured to the base and projecting through the base to the front thereof, circuit-controlling devices, and 65 means for detachably securing and electri-

cally connecting the circuit-controlling devices to the studs from the front of the base.

19. In a panel-board, a base, circuit-controlling devices, a bus-bar system located at the rear of the base, and conducting means 70 extending through the base to the front of the same and secured thereto for mechanically securing the bus-bar system in position, said means having provision permitting the securing and removal of said circuit-controlling devices to the base from the front thereof, the position and inter-relationship of said bus-bar system and base being unaffected thereby.

20. In a panel-board, a base, bus-bars and 80 branch conducting bars located at the rear of the base, conducting studs extending through the base to the front of the same for securing the said bars to the base, said studs being arranged in pairs and having 85 threaded sockets at the front of the base, a fuse-holding device for each pair of studs, and a pair of conducting screws associated with the contacts of the fuse-holding device for connecting the fuse-holding device to 90 the studs from the front of the base.

21. In a panel-board, the combination of an insulating base, bus-bars and branch conducting bars located at the rear of the base, 95 studs extending through the base from the front to the rear thereof and permanently connected to the said bars, said studs serving to clamp the bars to the base and having threaded sockets at the front of the base, said studs being arranged in pairs, a fuse-receptacle for each of said pairs of studs, and conducting screws associated with the respective contacts of the receptacle and adapted to engage the threaded sockets of the studs to secure the receptacle in place. 100

22. A panel-board comprising, in combination, a base, bus-bars located at the rear of the base, and anchor-studs secured to the bus-bars extending through the base to the front thereof and securing the bus-bars in 110 place, said anchor-studs having provision at the front of the base by which the electrical equipment of the board may be removably secured thereto and said anchor-studs securing the bus-bars in position independently of the electrical equipment to permit the mounting and removal thereof on the base without displacing the bus-bars. 115

23. In a panel-board, a base, a bus-bar system located at the rear of the base, conducting means extending through the base secured thereto and mechanically securing the bus-bar system to the base, independently of the electrical equipment secured to the front of the base, circuit-controlling devices on the front of the base connected to the bus-bar securing means and detachable therefrom without disturbing such securing means. 120

24. In a panel-board, a base, a bus-bar and 125

a branch terminal-connector located at the rear of the base, and a fuse-holding device detachably mounted on the front of the base, one of the contacts of the fuse-holding device being electrically connected to the bus-bar while the other contact is electrically connected to the branch terminal-connector.

25. The combination with an insulating base, distributing connectors secured upon the rear of said base, bus-bars secured upon

the rear of said base and spaced apart from the base to permit the passage thereunder of distributing connectors, a steel casing secured over said distributing connectors and bus-bars and upon the back of said base, and an insulating medium interposed between said casing and bus-bars.

In witness whereof, I have hereunto subscribed my name.

HENRY F. STARRETT.
